ISAAC COOK, OF PHILADELPHIA, PENNSYLVANIA.

Letters Patent No. 71,582, dated December 3, 1867.

IMPROVEMENT IN COW-MILKING MACHINE.

The Schedule referred to in these Letters Patent and making part of the same.

TO ALL WHOM IT MAY CONCERN:

Be it known that I, ISAAC COOK, of the city and county of Philadelphia, and State of Pennsylvania, have invented a new and useful Milking-Machine; and I do hereby declare that the following is a full, clear, and exact description of the same, reference being had to the accompanying drawing, and to the letters of reference marked thereon.

My invention consists in exhausting the air from the pail or bucket into which milk is received as it is milked from the cow, and in giving a raising and lowering motion to the teat-cups, and in the formation of the teat-cups, as is hereinafter shown and described. On reference to the accompanying drawing, making part of this specification—

Figure 1 is a side elevation,

Figure 2 an end elevation,

Figure 3 a plan view of the arrangement of the teat-cups, and

Figure 4 a sectional elevation of the teat-cup.

Similar letters refer to similar parts in the several views.

A is a vessel, answering the purposes both of a receiver, from which air is to be exhausted, and a bucket or pail, for containing milk as it is milked from a cow. B is an air-pump, set upright on the said receiver or bucket. C is a lever, which is hinged to the link D, vibrating on the projection *a* of the curved arm E, fixed to the bucket. The air-pump piston-rod F passes through and is attached to the lever C in an opening in it, and is guided by the boss *b* on the end of the curved arm E. G is a pedestal fixed to the bucket A, at right angles, or nearly so, to the lever C. H is a vertical rod, which passes through a corresponding opening in the end of the pedestal G. I is a hollow cap, fixed to the upper end of the rod H. *c c c* are hollow tubes, radiating from the said cap I. They terminate each in a short, hollow cylinder, *d*, to which the teat-cups K are fixed. L is a lever, whose fulcrum is at M, on the projection G. One end of it is forked to embrace the rod H or the adjusting-collar N on it. The other end of it is connected by the rod O to the lever C. P is an elastic tube, communicating respectively with the cap I and the receiver A. The length of it must be sufficient to allow of the teat-cups being adjusted to any height. The weight of the rod H, its appointments, and the teat-cups, is carried by the lever L, whose forked end takes into the groove in the adjusting-collar N. *e e e* are stop-cocks, in the several hollow cylinders *d d d*, respectively. They are for discontinuing the operation of the machine on one or more of the teats, while it is continued on the rest. *f* is a stop-cock in the hollow head or cap I, into which the pipes *c c c* from the cylinders *d d d* converge. It is for discontinuing the operation of the machine on all the teats at one and the same time, in case the cow be restless, or from any other causes.

The bucket or receiver A is placed beneath the cow, the same as an ordinary milk-bucket, the teat-cups immediately beneath the teats. The set-screw *g* on the collar N is then loosened, and the rod H raised until the teats take, each, into its respective teat-cup. The set-screw *g* is then tightened, securing its collar to the rod H, and preventing it from slipping, and thereby uncovering the teats. Then the cock H at the bottom of the bucket A is closed, and the cocks *e e e* on the cylinders *d d d* opened, as is also the main cock *f*. Vibrate the lever C, and the air-pump B gradually exhausts the air from the bucket or receiver A, and through the medium of the elastic tube P, the cap I, radial tubes *c c c*, cylinders *d*, and the teat-cups K, are also gradually exhausted of their air, which exhaustion of the air causes the teat-cups to fit the teats air-tight. The rod H, by means of the rod O and the lever L, alternately raises and lowers with the piston of the air-pump, which facilitates the operation of milking, and is similar to the stripping of a cow by a calf while sucking, or to the pulling of the teats by a milk-maid. As the air is gradually exhausted from the receiver, etc., the milk flows from each teat into the teat-cups, and through the pipes *c* into the head I; thence through the elastic tube P into the receiver or bucket A, from which it can be drawn by the cock *h*. The fulcrum M on the projection G should be adjustable in the direction of the length of the lever L, to regulate the lift of the teat-cups for free or hard-milking cows.

The teat-cups K are constructed, as shown in fig. 4, with tapering ends, or become gradually smaller in diameter towards their upper ends, which thinness of the upper ends enables them to fit the roughest teats, and

also to collapse sideways, thereby giving them a side pressure. The taper, as shown, is formed on the outside of the teat-cups, but can be either inside or outside.

What I claim as my invention, and desire to secure by Letters Patent, is—

1. An air-pump so combined with a milking-machine that the milk will be drawn into the receiver or bucket without passing into or through the said pump.
  2. Giving a raising and lowering motion to the teat-cups, while milking, substantially for the purpose shown.
  3. A stop-cock so combined with a cow-milker, and so arranged relative to the teat-cups that the operation of milking may be discontinued on all the teats at one and the same time.
  4. Bevelling or thinning the upper ends of the teat-cups, either inside or outside, as shown and described.
- In testimony whereof, I hereunto sign my name to this specification in presence of two subscribing witnesses.

ISAAC COOK.
